CLAIM

The ornamental design for umbrella handle with torch, as shown and described.

DESCRIPTION

FIG. 1 is a front elevational view of the umbrella handle with torch showing my new design;

FIG. 2 is a rear elevational view thereof;

FIG. 3 is a bottom plan view thereof;

FIG. 4 is a top plan view thereof;

FIG. 5 is a right side elevational view thereof;

FIG. 6 is a left side elevational view thereof; and,

FIG. 7 is a perspective view.

A cord depicted in phantom lines is shown for illustrative purposes only and constitutes no part of the design as claimed.
